GARBAGE RECEPTACLE

Pauline N. Battin, College Point, N. Y.

Application May 2, 1935, Serial No. 19,337

8 Claims. (Cl. 150—49)

This invention is a novel garbage receptacle of the class adapted for kitchen use and to be located handy for ready and frequent opening and closing, attachable for example to, and detachable from, a sink, table, cabinet or the like.

The general objects of the invention are to afford a garbage receptacle of the class referred to which will be handy, accessible and easily operated, small in bulk but expandible with increase of contents, and adaptable to ready emptying and cleaning. A particular object is to afford an article of the kind referred to which is portable, and adapted to be hung or mounted in a convenient location, and which in use is readily opened and closed for the reception of successive increments of garbage.

A further object is to afford a structure and mechanism of garbage receptacle which will permit quick and wide opening thereof to present a substantially horizontal receiving mouth, followed by a quick and tight closing of the device. Other and further objects and advantages of the present invention will be explained in the hereinafter following description of an illustrative embodiment thereof or will be apparent to those conversant with the subject.

To the attainment of such objects and advantages the present invention consists in the novel garbage receptacle and the novel features of arrangement, construction and operation herein illustrated or described.

In the accompanying drawing Figure 1 is a perspective view of a garbage receptacle embodying the present invention, shown in full lines in its open position and in dotted lines adjusted to its normal or closed position.

Fig. 2 on a small scale is a right elevation view of the same receptacle, but limited to the mechanical fittings, the sack or bag being omitted; the same indicated as removably mounted upon the side or apron of a table, beneath the overhang, the receptacle shown closed in full lines and open in dotted lines.

Fig. 3, on an enlarged scale, is a vertical section looking from the right, showing the disposition of the mouth of the bag or sack when in closed position.

Fig. 4 is a perspective view of a convenient form of hook plate attachable to a table and from which the receptacle hereof may be hung as indicated in Fig. 2.

Fig. 5 is a face view of a blank of rubber, fabric or other flexible material from which the bag or sack of Figs. 1 and 3 may be produced.

Referring to the illustrated details of an ex-

ample of the present invention, the receiving element consists of a depending sack or bag 10 shown in its wide open position in Fig. 1 but closed in Fig. 3 and in the dotted lines in Fig. 1; this sack preferably composed of flexible waterproof material such as rubber, rubberized cloth, or other sheet material, which should also be impermeable to odors and vapors and is strong enough to securely hold a quantity of garbage in wet condition, and even waste liquids. In some cases the sack might be constructed of a suitable strong impervious paper, having the advantage that it may be discarded and replaced with each use. A bag of rubber or rubberized material may be readily cleaned, and turned inside out for the purpose, the bag being readily detachable from the mechanical fittings as will be described.

The form of sack or bag which is preferred has a square upper opening or mouth, shown widely 20 opened in Fig. 1, and the bag is shown as consisting of a front wall 11 with opposite rear wall 12 and side walls 13. The front and rear walls are turned over and secured or stitched at 14 to form looped tabs or hems for the mounting of 25 the bag upon the mechanism. The bag so described may be cheaply manufactured, for example from a sheet material blank of a shape corresponding with Fig. 1; or a modified form such as indicated in Fig. 5. When constructed 30 of rubber the different parts of the bag or sack may be vulcanized together, or the entire sack may be molded or produced in one piece without seams.

The sack 10 is shown mounted in a readily detachable manner upon a pair of outstanding frame parts or rods 17 and 18 receiving respectively the front and rear hems or loops 14 of the sack. As will be clear from Fig. 1, the sack is merely threaded on to the rods and pulled into 40 place where it remains securely with the aid of slight enlargements or rings at the outer ends of the rods, over which the looped sections of the sack may be passed for the removal of the filled sack from the mechanism. By this arrangement 45 of opposite carrying rods 17 and 18, outstanding from the mechanism to be described, the bag may be widely opened for the reception of material or may have its mouth snugly closed by the approach and overlap of the rods 17 and 18, as best 50 seen in Fig. 3, the sides 13 of the sack collapsing inwardly, and the closed sack being substantially sealed against the outlet of vapors, by the movement of one of the frame rods to a position over the other as seen in Fig. 3.

The mechanism by which the sack opening and closing rods 17 and 18 are mounted and moved will now be described. The portable attachment as a whole is carried on a fixed back plate 19 preferably consisting of a narrow vertical channel, and which like the other mechanical parts is preferably composed of a light material as aluminum alloy. To receive the back plate 19 there is shown a permanent plate 20 having an inturned hook 21 at its upper end and having side flanges to receive between them the flanges of the channel plate 19. The hook plate 20 is shown in Fig. 2 as permanently attached to the apron or vertical board 22 of a kitchen table, below the table overhang, so that when collapsed or closed the entire mechanism and sack are accommodated beneath the table overhang. To engage rearwardly with the hook 21 of the hook plate 20 the channelled back plate 19 of the mechanism is provided with a top hook 23. The entire mechanism is thus held snugly against any displacement, except that its lower end may be tilted forwardly when desired, to permit the removal of the mechanism from the hook plate 20. In this sense the mechanism is portable and may be removed for cleaning etc.

The mountings or connections between the sack rods 17 and 18 and the frame back plate 19 may be varied, but the following is a convenient arrangement wherein gravity is caused to assist the operation of the mechanism. The back rod 17 is shown as outstanding from and carried by a heavy lever 24, while the front rod 18 is carried by a similar lever 25. These levers when open take oppositely inclined positions as seen in Fig. 1, but when closed assume substantially vertical positions. Each of the levers is preferably a channel, and the lever 24 is somewhat narrower than 25 so that when the mechanism is closed the channelled lever 25 and the channelled back plate 19 enclose the lever 24 and the members 27 and 30 to be described.

The connections and fittings of the rod carrying levers 24 and 25 may be as follows. These levers are pivoted to each other at 26. A swinging arm 27 extends from a pivot 28 on the back plate flanges to a pivot 29 on the lever 24. The linkage is completed by a channelled link 30 extending from a pivot 31 on the carrying lever 25 to a pivot 32 on the arm 27. The lever 25 and arm 27 may remain approximately parallel as also the lever 24 and the link 30, affording a parallelogram motion, but as will be later described a slight departure therefrom may in some cases be desirable.

It will be noted that in being adjusted from open to closed position the rods 17 and 18 and the sack are lifted from a lower to a higher level. This has the advantage that when the device is unlatched, as will be described, gravity affords a quick wide opening of the sack without further manual attention. This operation is secured by the described linkage in combination with a further arm 34 extending from the upper end of lever 24 to an axle 35 extending through the flanges of the back plate 19. This arm 34 and axle 35 are conveniently produced by extending the carrying rod 17 to the right, through and beyond the flanges of the lever 24, thence bending it rearwardly as the arm 34, and thence bending it leftwardly as the axle 35. When closed the rod 17 is received in the notches 36 formed in the flanges of the lever 25, as shown in Fig. 2 and in dotted lines in Fig. 1.

After the mechanism has been let down to the open position it may be readily manually closed by merely pressing inwardly and upwardly upon

the lever 25 or the rod 18. When in fully closed position the mechanism is preferably latched there by means of a gravity latch 37 pivoted near the top end of the back plate 19 and engaging in front of the top end of the carrying lever 25. When properly balanced a mere lifting of the latch 37 causes the forward and downward swinging of the parts and the opening of the sack.

In use, the latch need merely be touched by the hand or by a dish to be emptied. As the sack is lowered to its open position gravity assists its wide opening, and the dish may then be scraped clear and emptied into the sack, whereupon the sack may be closed by a push of the hand or dish, affording the sanitary closing as shown in Fig. 3. When the sack is sufficiently full it need only be slipped from the rods manually. It may have side straps or handles for carrying it, and at its bottom a strap or handle for emptying it into an outside or larger receptacle or other convenient place of disposal.

To take the opening impact a stop is provided for the opening movement. This is shown as an inclined extension 27a of the flanges of the arm 27, these flanges contacting against the back plate 19 when the sack is wide open, as shown in Fig. 1. However, the impact of this stop may be dispensed with by any cushioning means, or the linkage can be modified or rendered non-parallel so that while gravity initially assists the opening of the bag it may oppose the final opening movement, thus preventing impact. A balanced action results, relieving the strain on the sack and permitting the use of paper sacks.

To assure the inward bending of the sack sides 13 with the closing of the sack each side may be provided with a pair of hinged strips which bend inwardly during the closing movement.

While various arrangements of levers, links and arms may be devised to give the described movements, the particular linkage illustrated is simple and satisfactory, and may be redescribed as follows. The rear sack rod 17 is mounted at the higher end of the carrier or lever 24. This lever takes its inclined position when the sack is open it rises to a vertical position when the sack is closed. These movements of lever 24 are produced by the arms 34 and 27. The upper arm 34 is shorter than the lower arm 27, and the spacing of the pivots 28 and 35 is such that when added to the length of the arm 34 the sum will equal the length of the arm 27 plus the portion of the lever 24 which extends between the pivots 17 and 29. This portion of the lever 24 and the arm 34 are shown of substantially the same length, while the arm 27 is substantially the same length as the spacing between the fulcrums of the arms 34 and 27. This simple linkage completely controls the desired movements of the lever 24.

The lever 25, to secure the desired wide opening is pivoted at 26 to the extreme lower end of the lever 24. The extension of the lever 25 below said pivot is connected by the link 30 with the arm 27. This completes a quadrilateral, which may be approximately a parallelogram, so that in the opening and closing movements the carrier levers 24 and 25 form a V, taking opposite slants which change progressively to vertical until, with the complete closing of the mechanism both levers stand vertical, or substantially so, as well as the controlling arms and link.

In a somewhat different aspect the arm 34 controls the upward and rearward swinging of the rear sack rod 17, while the movements of the

front rod 18 on the lever 25 are controlled by both of the arms 34 and 27 through the levers 24 and 25 and the intermediate connection or link 30. The entire linkage or mechanism it will be noted is at one side only of the sack, namely the right hand side, the sack rods outstanding leftwardly therefrom, and their left ends being free for the removal and replacement of the sack.

There has thus been described a garbage receptacle which embodies the principles and attains the advantages of the present invention; and in part this application is a continuation of my prior application Serial No. 697,631, filed November 11, 1933. Many matters of arrangement, construction and operation may be variously modified without departing from the principles of the invention and therefore it is not intended to limit the invention to such matters except to the extent set forth in the appended 20 claims.

I claim:

1. A garbage receptacle comprising a rigid upright back member or plate, an impervious flexible sack having front and rear rods from which the sack depends by its mouth, and mechanism supported on the back member and carrying the sack rods, said mechanism shiftable between a lower open position with the sack rods spaced widely apart and a higher closed position with the sack rods closely adjacent, and comprising front and rear carrier links each swingable about a movable pivot for carrying the respective rods, said links pivoted to each other below the sack mouth, upper and lower arms supporting the rear link from the back member, and controlling its movements, and a connection extending from one of said arms to the front link for controlling its movements in coordination with the back link.

2. A garbage receptacle comprising a rigid upright back plate, an impervious flexible sack having front and rear rods from which the sack depends by its mouth, and mechanism supported on the back plate and carrying the sack rods, said mechanism shiftable between a lower open position with the sack rods spaced widely apart and a higher closed position with the sack rods closely adjacent, and comprising a carrier for each rod, said carriers pivoted to each other at a point below the rods, upper and lower arms pivoted on the back plate and supporting the rear carrier and controlling its movements, and a connection from one of said arms to the front carrier for controlling its shift from open to closed position in coordination with the back carrier.

3. A garbage receptacle comprising a rigid upright back member, an impervious flexible sack having front and rear rods from which the sack depends by its mouth, and mechanism supported on the back member and carrying the sack rods, said mechanism shiftable between a lower open position with the sack rods spaced widely apart and a higher closed position with the sack rods closely adjacent, and comprising an upper arm and a lower arm both pivoted on the back member, the upper arm carrying the rear rod between open or front position and a higher closed posi-

tion, a carrier or lever for the front rod, and connections between the two arms and said carrier, causing the front rod to swing rearward and upward in coordination with the swing of the rear rod and into a closed position adjacent thereto.

4. A receptacle as in claim 1 and wherein the front and rear sack rods are parallel and both supported at the same end only, the other ends being free, and the sack having front and rear ways slidable upon and from the rods, for application and removal.

5. A receptacle as in claim 2 and wherein the front and rear sack rods are parallel and both supported at the same end only, the other ends being free, and the sack having front and rear ways slidable upon and from the rods, for application and removal.

6. A receptacle as in claim 3 and wherein the front and rear sack rods are parallel and both supported at the same end only, the other ends being free, and the sack having front and rear ways slidable upon and from the rods, for application and removal.

7. A garbage receptacle comprising a supporting back plate, front and back parallel sack rods, a sack engaging and depending from said rods by ways permitting ready sliding removal, and mechanism holding said rods rigidly at one end only, and controlling the shift of said rods between open and closed positions, while maintaining them parallel; said mechanism comprising an arm pivoted upon the back plate and carrying the back rod, a carrier for the front rod, a second arm pivoted upon the back plate below the first arm, and links between said arms and said front rod carrier; whereby when open the bag may be slid horizontally from the free ends of the rods and replaced.

8. A garbage receptacle comprising a supporting back plate, front and back horizontal sack rods parallel to said back plate, a sack engaging and depending from said rods by ways permitting ready sliding removal therefrom, and mechanism holding said rods rigidly at one end only, and controlling the shift of said rods between open and closed positions, while maintaining them parallel whereby when open the bag may be slid horizontally from the free ends of the rods and replaced; said mechanism comprising an upper arm pivoted at a higher point upon the back plate and a lower arm pivoted upon a lower point thereon, the upper arm carrying directly the back rod and permitting it to swing up closely adjacent to the back plate and down and out to open position, the lower arm being swingable upwardly closely adjacent to the back plate and outwardly to an inclined open position, an upper link connecting swinging parts of the upper and lower arms and having an extension beyond the lower arm, a lever carrying the front rod and extending approximately parallel to the lower arm, said upper link extension being pivoted to said lever, and a lower link, approximately parallel to the upper link and pivoted to the lower arm and the lower end of said lever.

PAULINE N. BATTIN.
